PLASTERER'S GUIDE

Harry Oscar, New York, N. Y.

Application January 16, 1947, Serial No. 722,409

4 Claims. (Cl. 33—85)

1

This invention relates to a plasterer's guide. More particularly, this invention is concerned with a portable level or guide which may be repeatedly used in the plastering of wall surfaces immediately adjacent a door or window opening.

When plaster is to be applied to a wall surface, all door and window openings must be prepared in a manner to permit the application of plaster to the wall surface adjacent the edge of the frame defining the opening. This is usually done by nailing strips or slats of wood to the studs which form the opening so that they project outwardly of the studs the proper distance allowing for the thickness of the plaster base plus the coating of plaster to be applied thereto. The slats or strips are used as a ground or leveling means to insure a smooth plaster coating adjacent the edge of the opening. When the plastering operation is completed the slats or strips are torn out or left in place. In either case, this method involves a substantial amount of labor and expense to prepare each opening, as well as a waste of material, since the slats or strips cannot be used over again. Accordingly, it is an object of this invention to provide a plasterer's level or guide for door or window openings which may be fitted to the opening and after the plastering operation in connection with the particular opening has been completed, may be removed from the opening and used in a similar manner for other openings.

A further object of this invention is to provide in a device of the character described, collapsible guide means which may be readily transported in its collapsed condition yet may be easily opened up into a structure which is usable as a plasterer's level or guide for door or window openings.

Another object of this invention is to provide in a device of the character described, means for temporarily securing a plasterer's level or guide within a door or window opening during the plastering operation but which may be readily detached after the plastering operation has been completed.

Yet another object of this invention is to provide in a device of the character described, a plasterer's level or guide including side, header and bottom members, wherein the various members are hinged together whereby the device may be collapsed into compact form.

Still another object of this invention is to provide in a device of the character described, a plasterer's level or guide for door or window openings comprising a frame wherein the dimen-

2

sions of the frame members may be adjusted to suit the size of the door or window opening in which the frame is to be used.

Still a further object of this invention is to provide in a device of the character described, frame members which may have their depth adjusted to accommodate variations in overall thicknesses of walls, plaster bases, and the like.

Still a further object of this invention is to provide a strong, durable, compact device of the character described which shall be relatively inexpensive to manufacture, easy to manipulate and yet practical and efficient to a high degree in use.

15 Other objects of this invention will in part be obvious, and in part hereinafter pointed out.

The invention accordingly consists in the features of construction, combinations of elements, and arrangement of parts which will be exemplified in the construction hereinafter described, and of which the scope and application will be indicated in the following claims.

In the accompanying drawing, in which is shown various possible illustrative embodiments 20 of this invention,

Fig. 1 is a perspective view of the plasterer's level or guide in expanded form;

Fig. 2 is a perspective view of the guide shown in Fig. 1 in partially collapsed form;

Fig. 2A is a perspective view of the guide in collapsed condition;

Fig. 3 is a partial perspective view of a member of the plasterer's guide showing means for adjusting one of its dimensions;

Fig. 4 is a partial perspective view of a member of the plasterer's guide showing means for securing the guide in use;

Fig. 5 is a perspective view of a wall surface showing the installation of the plasterer's guide;

40 Fig. 6 is a perspective view of a plasterer's guide embodying the invention and illustrating a modified form of the invention; and

Fig. 7 is a perspective view of a header member which may be used in conjunction with the guide shown in Fig. 6.

45 Referring now in detail to the drawing, 10 designates a plasterer's guide for a door or window opening and the like. The guide 10 comprises a pair of similar side members 11, a header 12 and a bottom member 13. The side members 11 were rectangular in shape comprising an inner face 14, an outer face 15 and edge portions 16, 17 which constitute guide surfaces. The members 11 have a length substantially equal to the height of the opening in which the guide is to be used. Each

of the side members 11, is formed with a semi-circular opening 18 which is used as a hand hold and with an opening 19 for the purpose herein-after described. The members 11 are also formed with openings 20a within which leveling elements 20 are mounted for view from either of the faces 14, 15. The upper and lower extremities of the members 11 are formed with L-shaped recesses 21 on the inner faces 14 thereof, which extend to the upper and lower edges respectively of the members 11 for the purpose hereinafter described.

The header 12 comprises a pair of substantially rectangular sections 22, 23 which are interconnected by a hinge 24. The sections 22 and 23 comprise edge portions 16a, 17a, and are connected at their respective outer extremities to the upper ends of the side members 11 by means of hinges secured to the inner surface of the sections and the inner face 14 of the side members. The section 22 is formed with an opening 25a within which is mounted a leveling element 25. The header 12 has a length substantially equivalent to the width of a particular door or window opening. The width of the header member 12 is the same as the width of the side members 11. The width of these members is determined by the overall width of the studs plus the thickness of the plaster base plus the thickness of the plaster coating to be applied to the plaster base. In determining these dimensions, consideration is given to whether plaster is to be applied to one wall surface adjacent a door opening or if wall surfaces on either side of the opening are to be plastered.

The bottom member 13, is similar to header 12 in structure and comprises sections 26, 27 which are interconnected by a hinge spanning the adjacent lower faces of the sections. The sections 26, 27 are connected at their respective outer extremities to the lower portions of side members 11 by hinges 28 which are secured to the inner face 14 of the members 11 and upper face portions of the sections 26, 27. It will be apparent from a consideration of Figs. 2 and 2A that the hinge arrangement described, permits the guide 10 as a whole to be collapsed with the sections 22, 23 and 26, 27 folding inwardly towards each other thereby bringing the side members 11 towards each other as shown in Fig. 2A. When in the collapsed condition, a screw 29a which passes through the aligned openings 19 in the members 11 together with a wing nut 29 is adapted to maintain the structure in its collapsed condition, thereby permitting transportation by means of the hand holds 18.

When using the guide 10, the device is opened up and placed within the opening formed by the studding defining the openings and leveling the guide by the use of leveling elements 20, 25, as shown in Fig. 5. The device is temporarily secured in place by means of securing means 30 mounted within the recesses 21 on the side members 11. The securing means 30 comprises a pointed member 31 having an offset end portion 32. The member 31 is held within the recess 21 by means of staples 33 which permit vertical as well as rotary movement of the member 30. In the inoperative position the pointed portion of member 31 is short of the end portions of the side member and the offset portion 32 lies against the wall of the recess 21. When the guide 10 is in its proper position, the member 30 is rotated to bring the offset portion 32 away from the recess well and extending outwardly of face 14. Upon

striking the offset portion 32, the pointed portion of member 31 is driven past the end portions of side member 11 and into engagement with the studding or the like. When the guide 10 is to be removed from the opening, the member 30 is driven in the opposite direction, thereby withdrawing the pointed member 31 from its holding position. In lieu of the securing means 30, other temporary securing means may be used, such as nails or screws which pass through the faces of the side members 11, header member 12 or bottom member 13, into temporary engagement with the studding or the like.

It is desirable that the guide 10 be adapted for use with walls which differ in their overall thicknesses. To this end, the side members 11 may be provided with means for adjustably changing the effective width thereof. Accordingly, the members 11 may be provided with extensible edge members 34. The members 34 which are angular in cross section, comprise a wall 35 having a length equivalent to that of the member 11 to which it is attached, and a width equivalent substantially to the thickness of the member 11. A wall 36 extends from the wall 35 at right angles thereto and has a length coextensive with the length of the wall 35. The wall 36 is formed with elongated slots 37. The member 34 is mounted on the member 11 with the wall 35 overlying a face of the member and the wall 36 overlying the edge portion of the member. The member 34 is mounted on the member 11 for movement in a direction outwardly of the edge portion of the member 11, by means of a screw 38 passing through the slot 37 in member 34 and secured in the face of member 11. A nut 39 on screw 38 fixes the member 34 in the desired position. By moving the member 34 outwardly of the edge portion of the member 11, the effective width of member 40 may be accordingly increased and is limited only by the extent of the slot 37 in the wall 36 of the member 34.

When the member 11 is made of wood, a U-shaped metal nosing 40 may be secured to the edge portions and adjacent face portions of the member 11 and thereby serve as a base for the overlying member 34. It will be apparent from a consideration of Fig. 3 that the width of member 11 may be changed by the use of adjustable member 34 to take into account variations in the overall thickness of the studding and adjacent plaster base which defines the door or window opening. The member 34 may be mounted on either the inner face 14 or the outer face 15 of the members 11. It is understood that the means for making the effective width of members 11 adjustable may be also applied to sections 22, 23 of the header member, in a similar manner.

As shown in Fig. 5, plaster may be applied to the wall surface immediately adjacent the door opening, using the edge portions 16, 17, 16a and 17a of the guide 10 to guide conventional tools for spreading the plaster adjacent the opening. It is apparent that edge portions of the guide 65 may be used on either side of the opening.

In Fig. 6 there is shown a guide 10a embodying the invention and illustrating a modified construction. The guide 10a comprises a pair of spaced, parallel side members 50 interconnected at their upper extremities by a header member 51. Each side member 50 comprises a pair of similar sections 52, which are adjustably secured to each other in edge to edge relationship. Each section 52 comprises an elongated, substantially rectangular member of wood, metal or the like

comprising guide edges 52a and which is formed with a pair of cut out portions 53 along one edge thereof. The sections 52 are assembled in abutting relationship, with the opposed cut out portions 53 forming an elongated slot 54 between the sections in the upper and lower portions thereof. The sections 52 are adjustably held together by turnbuckle members 55 which span each of the slots 54 and engage the inner edge portions of the sections. The header member 51 comprises a pair of similar sections 56 which are formed with cut out edge portions 57 and which are adjustably secured together in edge abutting relationship by turnbuckles 58 interconnecting the edge portions 57. The end portions of the header member 51 is removably secured to the upper ends of the side members 50 by a disengageable pin joint or other means which will permit the separation of the header member from the side members. It will be apparent from a consideration of Fig. 6, that the width of the side members 50 and the header member 51 may be varied by simultaneously turning the turnbuckles 55, 58 in a manner to either spread the component sections apart or to draw them together. This adjustment is desirable to take care of variations in the overall thickness of walls.

It is desirable that the guide 10a be adaptable to door openings of different widths. Accordingly, provision is made for adjustably positioning the members 50 with respect to each other thereby permitting the use of the guide for door openings of different widths. To this end, a pair of bars 60 interconnect the upper portions of the members 50 below their upper extremities, with each bar engaging a pair of opposed sections 52 as shown in Fig. 6. Each bar 60 comprises a pair of rods 61, having their outer extremities secured to an aligned section 52 of the opposed members 50. The rods 61 are interconnected at their inner ends by a turnbuckle 62. It will be apparent that by rotating the turnbuckles 62 in the appropriate direction, the distance between the side members 50 may be suitably adjusted. In changing the relative width of the guide 10a by this means, it is necessary to supply header members 51 having a length appropriate to the desired spacing between the side members. Since the header member 51 is disengageably secured to the side members, the change can be made with a minimum amount of effort. The guide 10a is also provided with means for detachably securing the guide to the studding defining the door opening. To this end, clamping means 63 is secured to the lower portions of side members 50. The clamping means 63 is adapted to engage the edge portions of the studding against which the guide abuts.

The guide 10a may further include a modified form of header member 51a which is adapted to be adjustable lengthwise as well as widthwise, thereby dispensing with the need for providing replaceable header members of different widths. The header member 51a comprises four symmetrically arranged, adjustably interconnected sections 64 of wood, metal or the like. Each section 64 is formed with a cut out portion 65. The sections 64 are adjustably interconnected for lengthwise movement by turnbuckles 66. The sections 64 are further adjustably interconnected for widthwise movement by turnbuckles 67. The outer end portions of the sections 64 are provided with outwardly projecting pins 68. The header member 51a may be used in guide 10a in place of the header member 51. The header 51a is en-

gaged with the upper portions of side members 50 by means of the pins 68 which are received in appropriate openings in the members 50. When the width of the side members 50 is changed by means of turnbuckles 55, the width of a header member 51a is similarly changed by means of turnbuckles 67. When the spacing between the side members 50 is changed by means of turnbuckles 62, the length of header member is correspondingly and simultaneously changed by means of turnbuckles 66.

It will thus be seen that there is provided a device in which the several objects of this invention are achieved, and which is well adapted to meet the conditions of practical use.

As various possible embodiments might be made of the above invention, and as various changes might be made in the embodiments above set forth, it is to be understood that all matter herein set forth or shown in the accompanying drawing is to be interpreted as illustrative and not in a limiting sense.

If desired, the side members 11 may each be formed with a pair of through openings 18a to receive screws 18b for attaching the device 10 within the opening in which it is mounted. The screws 18b may be used either in supplement to the attaching devices 30 or instead thereof. The devices 10 or 10a may be made of wood, metal, plastic material or any other suitable material.

Having thus described my invention, I claim as new and desire to secure by Letters Patent:

1. A plasterer's guide comprising a frame having side bars and end bars extending between the ends of the side bars, said end bars each consisting of sections having outer ends hinged to the side bars for movement from a folded position flat against the inner side face of the side bars to an extended position, the meeting inner ends of said sections being hinged to each other for movement from a folded position flat against each other between the side bars to an extended position, said side bars having the end portions of their inner faces formed with recesses spaced from their ends and having reduced portions extending longitudinally of the side bars to the ends thereof, pins in said recesses extending longitudinally in the extensions thereof having sharpened outer ends and having inner end portions bent to form laterally extending handles, and clips in said recesses straddling said pins and rotatably mounting the pins for turning movement from a retracted position disposing the handles in the recesses transversely thereof to an extended position in which the handles project from the side bars, said clips also slidably mounting the pins for longitudinal movement from a retracted position to an extended position in which their sharpened outer ends project from the ends of the frame to anchor the frame in position for use.

2. A plasterer's guide comprising a frame having side bars and end bars, said end bars being formed of sections hinged to each other and to the ends of the side bars for movement from a folded position longitudinally of the side bars to an extended position between the side bars, pins extending longitudinally of the inner faces of said side bars and having sharpened outer ends, clips straddling said pins and slidably and rotatably mounting the pins, and handles projecting laterally from the inner ends of the pins and movable from a position flat against the side bars to an extended position laterally of the side bars, the handles when in an extended position

constituting members adapted to be struck and thereby move the pins longitudinally from a retracted position to an extended position.

3. A plasterer's guide comprising a frame having side bars and end bars, said side bars being formed with recesses in the end portions of the inner side faces and having portions extending to the ends of the side bars, pins in said recesses slidable longitudinally from a retracted position to an extended position and having sharpened outer ends, said pins being also rotatably mounted and having handles movable from a position in the recesses to an extended position in which they project out of the recesses and laterally from the inner faces of the side bars in position for effecting longitudinal movement of the pins.

4. A plasterer's guide comprising a frame having side bars and end bars, and pins carried by said side bars and extending longitudinally thereof, said pins being slidable from a retracted

5 position to an extended position in which they project from the ends of the frame, said pins having handles movable from a position close against the side bars to an extended position in which they project laterally from the side bars in a position adapting them to be struck and the pins thereby forced to their extended position.

HARRY OSCAR.
